(57) **CLAIM**

I claim the ornamental design for a spider shaped flexible food mold, as shown and described.

DESCRIPTION

FIG. 1 is a perspective view of my new design, with the view showing principally front and top features thereof;

FIG. 2 is an inverted right side view thereof;

FIG. 3 is a perspective view showing principally bottom and rear features thereof;

FIG. 4 is a bottom view thereof;

FIG. 5 is an inverted rear view thereof;

FIG. 6 is an inverted front view thereof; and,

FIG. 7 is a top view thereof.
